Attest for G. W. Fox

United States Patent Office.

GEORGE W. FOX, OF ST. JOSEPH COUNTY, MICHIGAN.

Letters Patent No. 66,823, dated July 16, 1867.

FARM-GATES.

The Schedule referred to in these Letters Patent and making part of the same.

TO ALL WHOM IT MAY CONCERN:

Be it known that I, GEORGE W. FOX, of the county of St. Joseph, in the State of Michigan, have invented a new and useful improvement in Gate-Hangings, which is designed to be used as farm-gates, in outer or cross-fences, and can be opened at any time over all ordinary obstructions, such as snow or unevenness of ground, by raising the gate on the hinge-bar above and clearing the obstruction, it can also be adjusted at any desirable height by means of the set-screw in the sliding-ring at the lower hinge; and I do hereby declare that the following is a full, clear, and exact description of the construction and operation of the same, reference being had to the annexed drawings, making a part of this specification, in which—

Figure 1 is a perspective view, and

Figure 2 an end section.

a represents the gate; *b* the post upon which the hangings are attached. The posts and gate are the same as in ordinary farm-gates, except that the posts are made higher. *c*, the hinge-bar, bent at each end at right angles, and extending through the post, is held by the nuts screwed on the ends. *d* is a hinge rest, encircling the bar *c*, and acts as a brace to the bar; it also extends through the post, and is held by the nut on the end. *e e'* are hinges, encircling the bar *c*, and fastened in the post of the gate proper. *f*, a ring fitting the bar, and having in it the set-screw *g*. This ring slides freely upon the hinge-bar, as do also the hinges *e e'*; and by lifting them up, and sliding the ring up to the lower hinge, it can be held at any height by turning the set-screw against the hinge-bar.

What I claim as my improvement, and desire to secure by Letters Patent, is—

A gate, having post *b*, hinge-bar *c*, rest *d*, hinges *e e'*, ring *f*, and set-screw *g*, arranged, combined, operating for the purpose and in the manner substantially as herein described.

GEORGE W. FOX.
